(57) CLAIM

The ornamental design for a vehicle mountable support for a portable grill, as shown and described.

DESCRIPTION

FIG. 1 is a prospective view of the vehicle mountable support for a portable grill with the grill shown in broken lines;

FIG. 2 is a front elevational view thereof;

FIG. 3 is a left side elevational view thereof;

FIG. 4 is a rear elevational view thereof;

FIG. 5 is a top plan view thereof; and,

FIG. 6 is a bottom elevational view thereof.

The broken line showing of environment is for illustrative purposes only and forms no part of the claimed design.
